CANTILEVER SUPPORT SHELF BRACKET

Lee Boltin, 50 W. 96th St., New York, N.Y.

Filed May 20, 1963, Ser. No. 74,970

Term of patent 14 years

(Cl. D54—1)

FIG. 1

FIG. 2

FIG. 3

FIG. 4

FIG. 6

FIG. 5

FIGURE 1 is a perspective view of a cantilever support shelf bracket embodying my new design.

FIG. 2 is an end elevational view of the cantilever support shelf bracket.

FIG. 3 is a top plan view of the cantilever support shelf bracket.

FIG. 4 is a side elevational view of the cantilever support shelf bracket.

FIG. 5 is a perspective view of a modified form of cantilever support shelf bracket embodying my new design.

FIG. 6 is a side elevational view of a portion of the

midsection of the cantilever support shelf bracket shown in FIG. 5.

I claim:

The ornamental design for a cantilever support shelf bracket, as shown and described.
